(57) **CLAIM**

The ornamental design for a closure, as shown and described.

DESCRIPTION

FIG. 1 is a front perspective view of a closure embodying our new design;

FIG. 2 is a front side elevation view thereof;

FIG. 3 is a right side elevation view thereof;

FIG. 4 is a left side elevation view thereof;

FIG. 5 is a bottom plan view thereof; and,

FIG. 6 is a top plan view thereof.

In the drawings, the broken lines depict a trigger sprayer that forms no part of the claim.
